COLLAPSIBLE FILING CABINET

Kurt Bonnie Karl Axel Lundberg, Malarvagen 1,
Box 5021, 141 05 Huddinge, Sweden

Filed June 7, 1974, Ser. No. 477,235

Claims priority, application Great Britain Dec. 11, 1973

Term of patent 14 years

Int. Cl. D6—04

U.S. Cl. D6—167

FIG. 1

FIG. 2

FIG. 1 is a front perspective view of the filing cabinet in open position for use, and

FIG. 2 is a front perspective of the cabinet in its fully-closed position.

The appearance of the collapsible filing cabinet from the left side is identical to that shown from the right side in the perspective view of FIG. 1. The back of the cabinet is plain and unornamented.

I claim:

The ornamental design for a collapsible filing cabinet, as shown and described.
